(57) CLAIM

The ornamental design for a latch as shown and described.

DESCRIPTION

FIG. 1 is a top perspective view of a latch according to a new design and shown in a closed configuration;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is another top perspective of the latch of FIGS. 1-8 shown in an open configuration; and,

FIG. 10 is another bottom perspective thereof.

The portions depicted in broken lines form no part of the claimed design.
